UNITED STATES PATENT OFFICE.

MORRIS L. CECIL, OF NEW YORK, N. Y.

ICE-CREAM DISHER.

Application filed March 2, 1926. Serial No. 91,668.

This invention relates to ice cream dishers and aims to provide a device which is easy and cheap to manufacture and assemble and in which the operating parts have a sturdy 5 construction and relation such that the device will not readily get out of order.

A further object is to provide an article of the kind referred to in which the operating spindle for the scraper is substantially 10 protected against contact with the fingers of the operator.

Other objects and aims of the invention, more or less broad than those stated above, together with the advantages inherent, will 15 be in part obvious and in part specifically referred to in the course of the following description of the elements, combinations, arrangements of parts, and applications of principles constituting the invention; and 20 the scope of protection contemplated will appear from the claim.

In the accompanying drawings, which are to be taken as part of this specification, and in which I have shown merely a preferred 25 form of embodiment of invention,

Figure 1 is a plan view of an ice cream disher embodying my invention;

Figure 2 is a view taken at right angles to the showing of Figure 1;

Figure 3 is an elevation of the scraper and scraper spindle detached;

Figure 4 is a sectional view taken on the line 4—4 of Figure 1; and

Figure 5 is a sectional view taken on the line 5—5 of Figure 3.

Referring to the numerals on the drawings, 1 indicates a spoon of preferred configuration, comprising a bowl 2 and a shank or handle 3. At the outer end of the shank is a grip 4, and 5 indicates a bearing piece on the shank inwardly of the grip 4 and provided with a bearing 6 which receives the end 7 of operating spindle 8. The spindle 8 is provided with a spiral groove 9 and has a cone-bearing 10, an end bearing portion 11 and a scraper 12, the latter being formed of a resilient strip of metal curved to conform to the inner surface of the bowl 2 and having at its outer end a trunnion 13 which is pivotally held in an aperture or bearing at the outer side of the bowl.

In assembling, the spindle end 7 is inserted in the bearing 6, the bearing portion 11 of the spindle is seated in the open bearing 14 formed in the proximate side wall of the bowl, and the trunnion 13 is snapped

into its bearing aperture in the far side wall of the bowl, and the outer end of the trunnion upset, sufficiently to maintain the relation of parts, but leaving the trunnion 60 free to rotate in its bearing. The parts are further held against accidental disengagement by means of a half round shield-piece 16 which overlines the spindle, and is provided at each end with a pair of apertured 65 lugs 17 corresponding with similar lugs formed on shank 3 and firmly connected thereto as by means of rivets 18. Preferably the end of the shield-piece nearest the bowl is interiorly formed to cooperate with 70 the cone-bearing portion 10 of the spindle, so that the spindle is resiliently held in alignment.

Surrounding the inner end of the spindle is a sleeve 19, this sleeve carrying a pin 20 75 which extends inwardly and engages in the spiral groove 9 of the spindle. Externally of the sleeve the pin is extended and enlarged as at 21, for engagement within a slot 22 provided in the shield-piece and a slot 23 80 formed in a lever 24 which is pivoted as at 25 on a bracket 26 that extends out from the shank 3. A spring 27 is applied to operate the lever 23 in one direction, and the lever is provided with a finger piece 28 that extends 85 rearwardly and laterally from the lever pivot, whereby the lever may be operated in an obvious manner, to move the sleeve 19 longitudinally of the spindle. Since the spindle is free to rotate relatively to the sleeve, but is restrained against longitudinal movement, it will be evident that movement of the lever against the force of its spring will bring about rotation of the spindle and consequent scraping movement of the scraper 12, the reverse movement, of course, taking place under the influence of the spring 27. Over-rotation of the spindle is prevented by contact of the pin 21 with the end of the slot 22.

It will be apparent that the device described has no exposed parts which are apt to injure the fingers of an operator. It is simple in construction, easily assembled, strong and durable.

Inasmuch as many changes could be made in the above construction, and many apparently widely different embodiments of my invention could be made without departing from the scope thereof, it is intended that all 110 matter contained in the above description or shown in the accompanying drawings shall

be interpreted as illustrative and not in a limiting sense.

It is also to be understood that the language used in the following claim is intended to cover all the generic and specific features of the invention herein described and all statements of the scope of the invention which, as a matter of language, might be said to fall therebetween.

I claim:

In an ice cream disher, the combination of a handle, a bowl on the handle, a scraper for the bowl, a spirally grooved spindle for the scraper, a bearing on the handle for one end

of the spindle, an open bearing in the bowl for the other end of the spindle, a shield-piece overlying the spindle and secured to the handle, said shield-piece being provided with a slot, a sleeve on the spindle, a pin carried by the sleeve and extending inwardly thereof into the spiral groove of the spindle and extending outwardly through the slot in the shield-piece, a spring-pressed lever pivoted to the handle and having a slot through which the said pin passes.

In testimony whereof I affix my signature.

MORRIS L. CECIL.
